UNITED STATES PATENT OFFICE.

BERTHA HERBERT HOLLEY, OF NEW YORK, N. Y.

DESIGN FOR A GARMENT FOR WOMEN.

50,622.

Specification for Design.

Patented Apr. 17, 1917.

Application filed November 16, 1916. Serial No. 131,806. Term of patent 7 years.

To all whom it may concern:

Be it known that I, BERTHA HERBERT HOLLEY, a citizen of the United States of America, and resident of New York, in the county and State of New York, have invented a certain new, original, and ornamental Design for a Garment for Women, of which the following is a specification.

Reference is made to the accompanying drawing in which Figures 1 and 2 represent front and side view of a garment for women, showing my new design.

I claim:

The ornamental design for a garment for women, as shown.

Signed at New York city in the county of New York and State of New York this 10th day of November, A. D. 1916.

BERTHA HERBERT HOLLEY.
